UNITED STATES PATENT OFFICE.

GEORGE H. BRUDER, OF WEYMOUTH, MASSACHUSETTS.

EMBROIDERY-HOOP ADJUSTER.

Application filed November 6, 1925. Serial No. 67,378.

This invention relates to new and useful improvements in adjusting devices, and particularly to devices for adjusting embroidery hoops.

- 5 One object of the invention is to provide an adjusting device for this purpose which is simple in construction, easy to operate, and which can be manufactured at a comparatively low cost.
- 10 Another object is to provide a device of this character which has no parts with which the fabric, or the embroidering thread may become entangled.

15 Other objects and advantages will be apparent from the following description when taken in connection with the accompanying drawing.

In the drawing:

20 Figure 1 is an elevation of a portion of an embroidery hoop showing the invention applied thereto.

Figure 2 is an enlarged vertical sectional view of the parts shown in Figure 1.

25 Referring particularly to the accompanying drawing, 10 and 11 represent the ends of the embroidery hoop, in connection with which the present invention is especially adapted for use. These ends 10 and 11 are disposed in the ends of a flat tubular guide member 12, said member having the registering elongated slots 13 and 14, in the upper and lower sides. Disposed outwardly of the meeting ends of the hoop is an elongated casing 15, longitudinally through 30 which is formed the bore 16, and formed transversely through the intermediate portion of the casing, and intersecting the bore, is an elongated opening 17. Formed on one end of the casing is an arm 18, which is bent to dispose its outer end on the end 10 of the hoop, where said arm is secured to the hoop by rivets. The extremity of the arm is formed with a point 19, which is buried in the hoop end, so that there will be 35 no projecting part for thread to catch upon. Secured to the other end of the hoop is a similar arm 20, and said arm has its other end threaded and disposed through the before-mentioned bore 16, of the casing 15.

Engaged on the threaded portion of the arm 50 20, and having portions of its periphery projecting through the opening 17, is a nut 21, the peripheral face of which is roughened to facilitate turning thereof. Formed on the casing 15, and extending into the adjacent opening or slot 13, of the tubular guide member 12, is a lug 22, which is upset inwardly of said tube, whereby said casing and tube are rigidly connected together. Also, by reason of the fact that the arm 18 is 55 secured to the end 10, of the hoop, the casing, hoop end, and guide 12 are connected together as a unit, thus preventing any relative movement between the tube and the hoop end 10. The other end 11, of the hoop, 60 however, is slid able in the other end of the guide 12, with the attached arm 20, so that when the nut 21 is rotated the said end 11 will be moved inwardly or outwardly, with respect to the tube, whereby to properly 65 clamp the hoop against the fabric, and the inner hoop 23.

It will be noted that the entire adjusting mechanism presents a perfectly smooth exterior, thereby obviating the annoyance of 70 the embroidering thread catching on the device. Furthermore, the device is adapted to be easily attached to the ordinary embroidery hoop, without modifications thereto.

75 The guide 12 is preferably seamless, therefore the necessity of the provision of the opening 14, to permit introduction of a tool to upset the lug 22.

80 What is claimed is:

A device for expanding and contracting a ring including a casing having an integral arm attached to one end of the ring and having a bore, an arm attached to the other end of the ring and having a threaded portion disposed in said bore, a nut on the threaded portion of the arm and projecting through the casing, the casing having an integral lug, and a tubular guide receiving the ends of the ring therein and having an opening in which said lug is upset.

85 In testimony whereof, I affix my signature.

GEORGE H. BRUDER.
